ATTORNEY.

UNITED STATES PATENT OFFICE.

KARL BUXBAUM, OF PHILADELPHIA, PENNSYLVANIA, ASSIGNOR TO
WALTER S. GANS, MILTON H. GANS, AND JOHN H. ANDREAS, OF
SAME PLACE.

BINDING ATTACHMENT FOR SEWING-MACHINES.

SPECIFICATION forming part of Letters Patent No. 570,121, dated October 27, 1896.

Application filed September 6, 1895. Serial No. 561,626. (No model.)

To all whom it may concern:

Be it known that I, KARL BUXBAUM, a subject of the Emperor of Austria-Hungary, residing in the city and county of Philadelphia,

5 State of Pennsylvania, have invented a new and useful Improvement in Binding Attachments for Sewing-Machines, which improvement is fully set forth in the following specification and accompanying drawings.

10 My invention consists of a binding attachment for a sewing-machine which is formed of novel parts, as will be hereinafter set forth, and pointed out in the claims that follow the specification.

15 Figure 1 represents a perspective view of a binding attachment or device embodying my invention. Fig. 2 represents a longitudinal section thereof on line xx , Fig. 1. Fig. 3 represents a vertical section of a portion on line 20 yy , Fig. 1. Fig. 4 represents a horizontal section of a portion on line zz , Fig. 1. Fig. 5 represents a vertical section of a portion of the base or bed plate with a leveling-screw therein.

25 Similar letters of reference indicate corresponding parts in the several figures.

Referring to the drawings, A designates the base of the device, the same being provided with slots A' for attachment to a sewing-machine.

30 On the side of the base A is the arm B, the outer end of which has the grooved gage C thereon, and the inner end has the limb D therein, said arm B being freely connected with the base A by the screw E, which passes through the slot E' and enters said base.

35 F designates a screw which passes through the limb D and enters the base A at a right angle to the screw E, whereby the arm B, and consequently the gage C, may be adjusted to and from the folders H and J, said screw F also carrying the jam-nut G for evident purposes.

40 The folders H and J consist of plates J' J², with inturned lips, the plate J' being adjustably attached to the base A by means of the screw K and pin L, while the plate J² is preferably rigidly attached to the base A by the screws or rivets, it being noticed that the gage 45 C is set back of the lips N of the folders.

50 In the plate J' are slots P and Q, through

which the screw K and pin L pass, respectively, by which provision said plate J' may be moved in opposite directions for adjusting the folders relatively to each other.

55

On the pin L is a washer R, which rests upon the plate J' and is pressed against the same by means of the spring S, which is interposed between washer and the nut T, the latter being fitted to the threaded portion 60 of the pin L, by which provision the tension of the plate J' may be adjusted, said plate being elastic or yielding.

In the base A are vertically-arranged screws U, whose points, which are below, are rested 65 on the plate of the sewing-machine, so that said base may be set true on said plate.

V designates an arm which is connected with the journal W, the latter freely entering the socket X on the base A, so that the arm 70 may be raised and lowered or vertically adjusted, said journal being adapted to be engaged by the screw Y, so as to retain said journal, and consequently the arm V, in adjusted position.

75 Rising from the arm V and secured thereto is a guide Z, consisting of the columns Z', between which is a slotted gage B', through which passes the screw C', so that said gage may be raised and lowered relatively to the 80 width of the band or binding material, the screw being provided with the head D' and nut E', whereby the gage may be clamped and thus held in adjusted position.

The arm V carries at its outer end the plate- 85 spring F', which partly enters between the columns Z' and is adapted to bear against the band or fabric G', (shown in full lines in Fig. 1 and dotted lines, Fig. 3,) said spring being engaged by the screw H' for adjusting the 90 pressure on the spring and consequently on the band or fabric.

95 The operation is as follows: The binding material is passed through the guide Z, with the gage B' thereover, so that said material moves true and uniform through said guide, its tension being regulated by the spring F' through the medium of the screw H', as has been stated. The binding material, with the fabric between the same, is now directed 100 through the folders N, and the material is properly turned over the fabric, and the two

are now conveyed to the needle of the machine, whereby the binding is stitched to the fabric. When the fabric or binding, or both, is of increased thickness, the plate J' yields, 5 and when the fabric or binding, or both, become normal said plate returns to its original position, owing to the action of the spring S and the elasticity of the plate J'. When it is desired to have fabric bound with material 10 of greater width on one side than the other, the plate J' is moved out, so that its lip N extends outwardly to a greater extent than that of the plate J².

The plate A is shown with a duplication of 15 parts, such as the folders, gage, adjusting features, &c., which may be of different sizes from the corresponding parts if so desired, so as to adapt the attachment to the binding of materials of different dimensions, thus 20 avoiding the employment of separate attachments for such purpose.

The device is serviceable for binding clothing, hats, and garments generally, suspenders, and other articles.

Having thus described my invention, what 25 I claim as new, and desire to secure by Letters Patent, is—

1. In a binding attachment a plate, a gage having a slotted side arm with a limb at its 30 end, an adjusting-screw in said limb and plate, and a clamping-screw in said arm, said parts being combined substantially as described.

2. In a binding attachment, a plate with a horizontal socket in its front end, an arm having a journal adjustably mounted in said 35 socket, a guide secured to said arm, and a gage supported on said guide, said parts being combined substantially as described.

3. In a binding attachment, a plate with a horizontal socket in its front end, an arm journaled in said socket, a clamping-screw for the journal of said arm, a guide secured to said arm, a gage supported in said guide, a spring secured to said arm, and means for 40 controlling said spring, said parts being combined substantially as described.

4. In a binding attachment, a main plate with a horizontal socket in its front end, folders on said plate, an arm with journal adjustable in said socket, a guide consisting of standards secured to said arm, a gage adjustable in said guide, and a spring with an end in said guide, said parts being combined substantially as described.

5. In a binding attachment, the arm V having the journal W mounted in the socket X, in the base thereof, the guide Z on said arm, the gage B', in said guide, the spring F' on said arm adjacent to said guide, and the 50 set-screw H', in the arm and engaging said spring, substantially as described.

KARL BUXBAUM.
